**COMBINATION COMPUTER, ON-LINE KEY-
BOARD, MULTIFUNCTION DOCUMENT
CARD UNIT AND PRINTER**

Roger E. Abernathy, Boca Raton, Fla., and Wayne L. Aderman, Zumbro Falls, Theodore F. Dunnington, Oronoco, and Francis A. Goplen, Zumbrota, Minn., Edward R. Wiener, Vestal, N.Y., and Frank Wilkey, Jr., Rochester, Minn., assignors to International Business Machines Corporation, Armonk, N.Y., a corporation of New York

Filed July 29, 1969, Ser. No. 18,454

Term of patent 14 years

Int. Cl. D14—02

U.S. Cl. D26—5

FIG.1

FIG. 2

FIG. 3

FIG. 4

FIG. 5

FIG. 1 is a top plan view of a combination computer, on-line keyboard, multifunction document card unit, and printer showing our new design;

FIG. 2 is a front elevational view thereof;

FIG. 3 is a rear elevational view thereof;

FIG. 4 is a left side elevational view thereof; and

FIG. 5 is a right side elevational view thereof;

We claim:

The ornamental design for a combination computer, on-line keyboard, multifunction document card unit and printer, as shown.
